UNITED STATES PATENT OFFICE.

WILLIAM C. OWEN, OF CLEVELAND, OHIO.

DESIGN FOR A TIRE-CASING.

54,330.

Specification for Design.

Patented Dec. 23, 1919.

Application filed March 11, 1919. Serial No. 282,045. Term of patent 7 years.

To all whom it may concern:

Be it known that I, WILLIAM C. OWEN, a citizen of the United States, residing at Cleveland, in the county of Cuyahoga and State of Ohio, have invented a new, original, and ornamental Design for Tire-Casings, of which the following is a specification, reference being had to the accompanying drawing, forming part thereof.

Figure 1 is a plan view of a portion of a tire-casing showing my new design and Fig. 2 is a sectional view of same on the line 2—2 of Fig. 1.

I claim the ornamental design for a tire-casing, as shown.

WILLIAM C. OWEN.
